UNITED STATES PATENT OFFICE.

ALBERT T. BELL, OF NEW YORK, N. Y., ASSIGNOR TO THE B. F. GOODRICH COMPANY, OF AKRON, OHIO.

DESIGN FOR A DISPLAY AND SALE CABINET.

SPECIFICATION forming part of Design No. 34,405, dated April 23, 1901.

Application filed March 6, 1901. Serial No. 50,142. Term of patent 14 years.

To all whom it may concern:

Be it known that I, ALBERT T. BELL, a citizen of the United States, residing in the city, county, and State of New York, have invented and produced a new, useful, and original Design for a Display and Sale Cabinet, of which the following is a specification, reference being had to the accompanying drawing, forming part thereof.

10 The drawing illustrates a perspective view of such display-cabinet, showing its shape and configuration.

As shown in the drawing, my design consists, substantially, in the representation of a 15 Greek temple of the Doric order of architecture. The leading or material features of my design are a stepped base A, supporting the cabinet, whose front elevation represents a portico having two vertical plain-faced pilas-

ters B B, supporting the pediment C, from 20 whose apex extends the ridge-piece of the roof D, the roof extending horizontally on either side of this peak in wings E. Across the front of the portico, from side to side of the cabinet behind the pilasters B B, are tray 25 or box shelves F F.

Having described my invention, what I claim as new, and desire to secure by Letters Patent, is—

The design for a display and sale cabinet 30 as herein shown and described.

In witness whereof I have signed my name to this specification in the presence of two subscribing witnesses.

ALBERT T. BELL.
